[57] CLAIM

The ornamental design for a pipe, as shown and described.

DESCRIPTION

FIG. 1 is a side elevational view of a pipe showing my new design, the opposite side elevational view being a mirror image;

FIG. 2 is a rear elevational view thereof;

FIG. 3 is a front elevational view thereof;

FIG. 4 is a top plan view thereof;

FIG. 5 is a bottom plan view thereof;

FIG. 6 is a perspective view thereof;

FIG. 7 is a side elevational view of a pipe showing my new design in its open condition for the purpose of a complete disclosure, the opposite side elevational view being a mirror image;

FIG. 8 is a rear elevational view thereof;

FIG. 9 is a front elevational view thereof;

FIG. 10 is a top plan view thereof;

FIG. 11 is a bottom plan view thereof;

FIG. 12 is a perspective view thereof.
